UNITED STATES PATENT OFFICE.

FRANK O. WOODLAND, OF WORCESTER, MASSACHUSETTS.

INTERNAL-COMBUSTION ENGINE.

1,131,587.

Specification of Letters Patent.

Patented Mar. 9, 1915.

Application filed March 22, 1912. Serial No. 685,580.

To all whom it may concern:

Be it known that I, FRANK O. WOODLAND, a citizen of the United States, residing at Worcester, in the county of Worcester and State of Massachusetts, have invented a new and useful Internal-Combustion Engine, of which the following is a specification, reference being made therein to the accompanying drawings.

10 This invention relates to the novel construction and peculiar combination of the cylinder and piston mechanism, and to the manner of arranging the various ports and passages for effecting the delivery and action 15 of the explosive fuel or combustion elements, in the manner more fully hereinafter explained; the objects being to produce a simple, desirable and efficient internal-combustion engine of the two-cycle type, and adapted 20 for employment in automobiles, auto-trucks, motor-boats, and for other motor purposes.

Another object is to provide a two-cycle combustion engine, wherein the charge of 25 explosive mixture is taken into a primary chamber within the upper end of the cylinder, there primarily compressed within the said cylinder chamber, and by the single piston element, and delivered directly through 30 the wall of the piston into the combustion chamber within the tubular piston, without other element acting as a valve and during the downward or power stroke.

Another object is to provide, in combination with an internal-combustion engine cylinder having an annular primary chamber in its upper part, and a unitary tubular piston into which the charge is passed from 35 said primary chamber by downward or power stroke; of means such as described for the circumferential introduction of air at the junction or passway from said primary chamber to the piston-chamber, and between the incoming charge and the spent charge.

45 I attain these objects by mechanism, the nature and operation of which is illustrated in the accompanying drawings; the particular subject matter claimed being hereinafter definitely specified.

50 In the drawings, Figure 1 represents a central vertical section of a two-cycle internal-combustion engine, embodying my invention. Fig. 2 is a partial sectional view showing a slight modification of the fuel- 55 supply ingress; and with the piston at its elevated position. Fig. 3 is a transverse sec-

tion at line W, through the ingress port. Fig. 4 is a transverse section at line X of the intermediate port and air inlet. Fig. 5 is a transverse section at line Y, through the 60 exhaust passages. Fig. 6 represents, on a smaller scale, a horizontal section of a plurality of cylinders as adjacently associated or cast *en bloc*, and showing a manner of connecting their top chambers in common, 65 by cross passages. Fig. 7 represents a vertical sectional view of the engine embodying my invention, with air inlet means omitted. Fig. 8 is a vertical section view showing a modification in the end form of the internal 70 cylindrical element. Figs. 9 and 10 represent, on somewhat larger scale, fragmentary section views of the piston, illustrating modification in the construction of the inlet ports, and Fig. 11 is a fragmentary cross-section 75 of the ports shown in Figs. 9 or 10.

In accordance with my present invention the engine-cylinder, indicated by numeral 1, is formed with a dual bore; that is, with portions of its length made of different internal diameters; the upper part, or that end of the cylinder which is farthest from the crank-shaft, being of larger diameter than the lower portion, or end of the cylinder nearest the crank-shaft; the two internal cylindrical surfaces being co-axial and meeting at an intermediate position with an annular offset 8, which may be approximately square and perpendicular to the axis, or of other suitable form, as an inclined or rounded offset. The length of each of the said different diameter portions is somewhat greater than the length of the stroke or distance traveled by the piston. The lower part of the cylinder is best provided with water-jacket spaces 4, while at the upper portion such jacket spaces may be omitted.

In this specification the terms "upper" and "lower" ends of the cylinder or piston refer to the parts as located upon the accompanying drawing; but it is obvious that in variously situated engines the cylinder may be used in either upright, horizontal, oblique, or inverted position. It will therefore be understood that in whichever instance or position it is employed, the term "upper" signifies the end of the cylinder or piston farthest from the crank-shaft, and the term "lower" signifies the end nearest the crank-shaft.

The cylinder-head is provided with an internal cylindrical body or element 14 that

extends into the larger diametered portion of the cylinder, concentric therewith, and suitably fitting the internal diameter of the piston tube. The inner end of said element 5 14 terminates at or near the position of the offset 8. This construction provides an annular chamber 13 within the upper part of the cylinder, in which chamber an annular member of the piston works.

10 The piston 5 is of single tubular form, with a head or disk 5^x located in and rigidly united therewith at a predetermined position in its length; the tubular portion extending upward as a plain cylindrical shell 15 for the required distance above the position of said disk; the tubular body being of a diameter to match the lesser diameter of the cylinder. Its upper end is provided with an annular head, flange or member 15, preferably integral therewith fitting the chamber 13 within the larger diametered portion 20 of the cylinder. The peripheral edge of said flange is best made of suitable dimension for containing one or more packing 25 rings 7.

Ports 3 are formed in the piston adjacent to the disk 5^x, which ports register with exhaust ports or passages 33 of the cylinder, when the piston is at the lower or outward 30 end of its stroke. Said piston is also provided near its upper end with ports 2 which register with a circumferential space or pass-way 22 in the cylinder, when the piston is near the outward end of its stroke; said 35 ports 3 and 2 being relatively positioned to afford the desired lap or lead in respect to the ports 33 and 22.

The ports 2 of the piston are preferably 40 formed to comprise a ring fully around the piston, but with sufficient solid material to strongly connect the parts of the piston which are above and below the ports. The space 22 and the ring of ports 2 permit entrance of the charge from chamber 13 into 45 the interior of the piston 5 centripetally from all sides at the same time, and closely adjacent to the end of the inside element 14 of the cylinder-head. The combustion chamber F is the space within the tubular 50 piston between the piston-head 5^x and the end of said inwardly extending element 14. The area or capacity of the chamber 13 is made somewhat greater than the area or capacity of the combustion chamber F within 55 the piston tube.

The ingress passage or port 10 from the carbureter C enters the upper end of the cylinder; which latter is provided with 60 grooves 11 or portions of larger diameter that extend down the sides thereof to a position somewhat below the position to which the annular head-flange of the piston rises when the piston is at the upper end of its stroke. Said grooves permit the explosive 65 gas to pass from the upper part of the

chamber to the annular compression space beneath the flange 15 of the piston, when the latter passes the ends of said grooves as the piston is elevated. The carbureter C can be of any approved type, and is not therefore herein shown in detail. The engine shaft 16, crank 17, and connection bar 18, coupling the crank with the piston, may be of well known construction and arranged substantially as shown. The crank case 19 75 may be employed merely as a protecting guard, or a receptacle for oil; or may be entirely omitted if in any instance preferred. Suitable ignition devices or spark-producing means are employed having terminals at 80 6 for firing the charge. The ignition means may be of any approved construction, and to operate in well known manner.

As illustrated in Figs. 1-4, the circumferential chamber or passage 22 is arranged 85 in the body of the cylinder, adjacent to the offset 8, and surrounding the piston 5. From said space a pass-way or port 23 communicates with the annular chamber 13. An air inlet way 20 leads from the exterior 90 of the cylinder into said space at a position preferably opposite the pass-way 23; said inlet being provided with an inwardly opening spring-pressed valve 21 that admits air to the chamber 22 when the partial vacuum 95 or interior suction reaches a degree that overpowers the tension or resistance of the spring 26. Suitable means, as a threaded stem and nut, is provided for regulating the tension of the spring. The space 22 is preferably enlarged at one side, as best shown in Fig. 4; the passage 23 connecting with the annular chamber being opposite the valve and air inlet way. By constructing the passages and chamber 22 as shown, it is 100 possible for the admitted air to normally assume and occupy the chamber space without passing up the pass-way 23. Then when the ports 2 come into registering relation 105 therewith, the explosive mixture flowing from the chamber 13 drives the mass of air into the combustion chamber F in advance of said explosive mixture, so as to form the intermediate air barrier between the fresh 110 and spent gases within the combustion chamber, in a regular and comparatively uniform manner.

In some instances my invention can be embodied in an engine without employing the feature of the air inlet means; and I have 115 illustrated such a construction of my invention in Figs. 7 and 8. As shown therein the bottom end of the element 14 is disposed at a level sufficiently above the offset 8 to substantially correspond with the vertical dimension of the piston ports 2; so that space 120 is afforded for the charge to pass from the compressing chamber 13 directly into the upper part of the combustion chamber F when the ports 2 descend into conjunction 125 130

- therewith. In this instance the charge is primarily compressed between the offset 8 and the head flange 15, which latter is placed at somewhat greater distance above the offset than in the instance illustrated in Fig. 1; so that space or room for the charge is provided wholly within the annular chamber 13 instead of the space 22 which is, in this form, dispensed with. The end of the 10 interior element 14 can, if in some instances desired, be made approximately conical, as indicated at 9, on Fig. 8; or in other instances it can be made flat, as shown in Fig. 1, or convex as in Fig. 7; the idea of the 15 conical shaped end being to cause a sure clearance of the spent gases away from the head of the chamber when the in-coming charge enters from the circumferentially disposed ports.
- 20 In Fig. 2 the air-inlet valve 21 and space 22 is dispensed with, and small holes 27 are formed through the cylinder shell, abutting upon the piston. At a proper position upon the tubular piston there are formed longitudinal grooves 29 that co-act with said holes when the piston is elevated, to open a passage from said holes into the chamber 13, for admitting a small volume of air there-to, closely adjacent to the offset 8. This is 25 a modification of somewhat simpler construction, embodying the compressing chamber at the upper part of the cylinder, and makes a simple inlet-controlling means available in engines where it is desired to employ 30 an in-flow duct or an air-inlet adjacent to the bottom of the compressing chamber 13. The ingress ports 2 of the piston can, when so desired, be formed as a circumferential series of closely adjacent narrow longitudinal slits, as indicated at 2^x in Fig. 9; or said ports may consist of an encircling cluster or groups of adjacently drilled small holes, perforations or reticulated area, as Fig. 10; said holes or slots being of a degree 35 of fineness that will prevent the passage of flame, or back-firing, from the chamber F to the chamber 13, so that the preliminary charge will not become ignited from the hot spent gases.
- 40 In a multi-cylinder engine, that is where two, three, four or more cylinders are associated or cast *en-bloc*, the upper chambers 13 of the several cylinders are preferably connected in common by open passways 31 into each other, as indicated in Figs. 6 and 8, or with a manifold C^x having a common passage from the carbureter. By thus connecting the tops of the annular chambers with each other, the pressure above the piston heads 15 is equalized and resistance to the upward movement of the piston, which might otherwise occur, due to confinement of gas in the top space of the chamber, is obviated; since the surplus volume from one 45 chamber passes to another, and vice versa, as the several pistons rise and fall; while at the same time the normal draft on the carbureter is maintained.
- For single cylinder engines the ingress port 10 is preferably located to enter the chamber 13 just below the position assumed by the annular piston-head when at the upper limit of the stroke. (See Fig. 2.) In such an instance the upper part of the chamber can have an opening to the exterior of 75 the head.
- The operation of my improved mechanism is as follows: When the piston moves upward the ports 2 become closed and partial vacuum is produced beneath its annular head 15, within the chamber 13 and the space 22. As the degree of suction becomes sufficient to overcome the resistance of the spring 26 the valve 21 opens and admits a 80 small volume of air into the space 22; but at about the same instant the head 15 of the piston passes over the grooves 11, giving opening thereto, and the explosive gas 85 rushes from above into the chamber beneath the annular-head 15 and fills the same for a 90 charge. Then as the piston descends this charge is primarily compressed in the chamber 13, between the annular head of the piston and the offset 8, until the ports 2 register with the circumferential space 22, or 95 come below the end of the interior cylindrical element 14; the ports 3 having then partially opened to the exhaust 33, before the ports 2 open, then the compressed charge 100 expanding flows through the ports 2 into the combustion chamber F, centripetally from all sides of the circle, and closely adjacent to the end of the element 14; the inlet air entering from space 22 in advance of the explosive mixture. At the same time and 105 movement a quantity of explosive mixture is pumped into the upper chamber of the cylinder from the carbureter C, for a succeeding charge. The incoming charge, entering through the ports 2, drives out from 110 the chamber F the remnant of the spent gases through the open exhaust, thereby effecting a practically complete scavenging of the chamber F, as it becomes filled with the 115 fresh charge. The air, when admitted, forms a barrier mass between the spent product and fresh mixture, preventing the mingling of the same, or the firing of the fresh charge by the hot spent product. The charge within the combustion chamber is 120 compressed as the piston moves upward, and at the proper instant said compressed charge is ignited and exploded by the sparking means 6, as will be fully understood; thereby throwing down the piston and repeating 125 the operation as above described. In the engine constructed without the air-means the operation is substantially the same as above described, excepting that no air barrier is introduced between the explosive mixture 130

and spent gases as the charge enters the combustion chamber.

It will be observed that the primary compressing of the charge is accomplished by 5 and during the downward or power stroke of the piston and its transfer into the combustion chamber to replace the exhaust charge, occurs at the end of said stroke. It may also be noted, that with the construction herein set forth the feed or movement 10 of the explosive mixture, from the ingress 10 to the exhaust ports 33, is practically direct, or continually in one general direction; the flow passing bodily from one end of the 15 chamber to the other, and no counter currents are established, within the combustion chamber, tending to commingle the fresh gases with the spent gases; while the adjacency of the pumping or compression chamber 20 and the combustion chamber is such that there is no loss of power or volume in the manipulation of the charge; hence an efficiency of action, an effective explosion, and a very complete scavenging result is attained.

What I claim and desire to secure by Letters Patent, is—

1. In an internal-combustion two-cycle engine, in combination, a dual-bore cylinder, 30 its upper portion being of larger internal diameter than its lower portion, the cylinder head provided with an internal cylindrical element extending within the larger diametered portion of the cylinder and into 35 the piston, affording an annular chamber including a fuel-receiving chamber and a compression chamber within the upper part of the cylinder, the fuel supply conduit leading into the upper part of said chamber, a 40 tubular piston having a piston-disk fixed therein, its tubular body fitting the smaller diametered portion of the cylinder, and extending into said annular chamber about said internal cylindrical element, and provided with an annular flange-head fitting 45 within the chamber, said piston having exit-ports adjacent to the inner face of its piston-disk that register with exhaust ports in the cylinder, a series of ingress-ports located 50 below said annular flange-head for passage of the charge from the cylinder chamber through the tubular part of the piston into the combustion chamber, said ports positioned to open when the piston approaches 55 the limit of its downward stroke.

2. In an internal-combustion engine of the two-cycle type, the engine-cylinder formed with the internal diameter of its upper portion larger than the internal diameter of its 60 lower portion, and with an intermediate annular offset, an interior cylindrical element carried by the cylinder head and projecting within the larger diametered portion of said cylinder, affording an annular compression 65 chamber and charge-receiving chamber

therein, the end of said element being near the edge of said offset, with a circular space between; a reciprocating unitary tubular piston movably fitting the smaller diameter of the cylinder and the exterior of said inwardly projecting element, and having an interior disk, and an upper head-member fixed on the tubular piston and fitting the annular chamber, said piston forming a combustion-chamber and means for the passage of the charge from the receiving chamber above, to the compression chamber below said head member, and provided with exist-ports at the base of its chamber, and having near its upper end ingress ports that come into open relation adjacent to the end of said interior cylindrical element by downward stroke of the piston.

3. The combination of an engine cylinder provided with an internal cylindrical element, an annular chamber at its upper end surrounding said element, and an open lower end; a tubular piston having a disk, exit ports in the wall of the piston adjacent to said disk, and an upper annular outwardly projecting head that works within said annular chamber, said piston also provided with a ring of ports disposed therein at a position to uncover or become open at or near the end of said internal element, and means for delivering the fuel medium into said annular chamber and a by-pass therefor from above to beneath the annular head of the piston, when at the upper end of said cylinder, substantially as set forth.

4. In an internal-combustion engine of the two-cycle type, an engine cylinder including a pumping and compressing chamber within said cylinder, a reciprocating tubular piston having the combustion chamber located 101 therein, and provided with means for compressing the charge of explosive mixture within said pumping chamber, said cylinder having the inlet for the explosive mixture at the upper end of the pumping chamber, the interior of the cylinder being provided about the upper part of said chamber with recesses that terminate somewhat below the inlet opening, and a pass-way at the lower end of said pumping chamber for transferring said charge directly therefrom into the combustion chamber, by and during the downward or power-stroke of the piston.

5. In a two-cycle internal-combustion engine, the combination of the dual-bore cylinder having the greater internal diameter at its upper end, and an intermediate annular offset, an internal cylindrical element fixed within said cylinder and affording an annular chamber at the cylinder head, the reciprocating tubular piston having an annular flange-head surrounding said internal element within the cylinder chamber, the upper part of said cylinder chamber having an internal area of greater diameter than 125 130

- said flange head, to permit gas to pass the piston-head when near the top of said chamber, means for supplying explosive gas into the upper part of said chamber, said flange 5 head of the piston acting to cut off the inflowing charge for compression, the piston tube being provided with ports for the passage of said gas from said chamber to the interior of the piston when at a predetermined position.
6. In an internal-combustion engine, in combination, the engine cylinder having its upper portion formed of larger internal diameter than its lower portion, with an intermediate annular offset at the junction of the respective internal diameters, an internal cylindrical element co-axially disposed within the larger diametered part of said cylinder and extending into the piston, a reciprocating tubular piston having upper and lower ports therein, and an annular flange-head working within the chamber about said internal cylindrical element for primarily compressing the explosive charge above said offset, said cylinder having an interior space adjacent to and beneath said offset and communicating with said annular chamber and a passage through the wall of the cylinder for admitting air into said interior space to combine with the charge within the cylinder adjacent to said offset.
7. In a mechanism of the class described, in combination, with the dual-bore cylinder having the intermediately disposed offset, and the reciprocating tubular piston inclosing the combustion chamber, and having a circumferential ring of ingress-ports thereinto; the body of said cylinder provided with a piston-surrounding port or chamber positioned for registering with said ingress ports, said chamber being formed eccentric to the piston axis, and having an air-inlet way thereinto at one side, and a passway thereinto from above said offset at its other side, and means for controlling the admittance of air through said air-inlet way.
8. In an internal combustion engine, an engine-cylinder having an inwardly projecting concentric cylindrical interior element fixed to the cylinder head, and provided with an annular charge receiving chamber and compressing chamber surrounding said element within the upper part of the cylinder; a reciprocating tubular piston including the combustion chamber, and having means for primarily compressing the explosive charge within said annular chamber, said piston being provided with a circumferential row of ingress ports, the port area being composed of a multiplicity of small openings formed in the tubular wall of the piston, and of such fineness and adjacence as to afford a fire-resistant barrier across the port area, coincident with the tubular wall.

Witness my hand this 20th day of March 1912.

FRANK O. WOODLAND.
